Primary Examiner — Wan Laymon*Assistant Examiner* — Clint A Samuel(74) *Attorney, Agent, or Firm* — Knobbe Martens Olson & Bear LLP(57) **CLAIM**

The ornamental design for a valve frame for a delivery system, as shown and described.

DESCRIPTION

FIG. 1 is a perspective view of a valve frame for a delivery system;

FIG. 2 is a front side view of a valve frame for a delivery system of FIG. 1, wherein the rear side view of a valve frame for a delivery system of FIG. 1 is identical;

FIG. 3 is a side view of a valve frame for a delivery system of FIG. 1, rotated 15° with respect to the front side view of FIG. 2;

FIG. 4 is a top view of a valve frame for a delivery system of FIG. 1; and,

FIG. 5 is a bottom view of a valve frame for a delivery system of FIG. 1.
